United States Patent Office

Des. 193,315
Patented July 31, 1962

193,315

SLIDE PROJECTOR

Herbert S. Barnhart, Scarsdale, N.Y., assignor to Minneapolis-Honeywell Regulator Company, Minneapolis, Minn., a corporation of Delaware

Filed Aug. 7, 1961, Ser. No. 66,232

Term of patent 14 years

(Cl. D61—1)

Fig 1

Fig 2

Fig 3

Fig 4

FIGURE 1 is a front perspective view of a slide projector, showing my new design,

FIGURE 2 is a rear elevational view thereof,

FIGURE 3 is a bottom plan view thereof, and

FIGURE 4 is a left side elevational view thereof.

I claim:

The ornamental design for a slide projector, substantially as shown.
